6 Claims. (Cl. 253—39.15)

1

This invention relates to the manufacture of blades for that kind of gas turbine having an axial flow bladed rotor assembly whose blades are made separately therefrom and are retained thereon by fixing their roots at anchorages provided on the rotor, and to the manner of attachment of the blades in machines of that type. The invention relates in particular to the use of hollow tubular blades of "sheet" metal, which expression is used herein and in the appended claims to mean metal of such thin section as to be susceptible of local shaping by pressing, stamping, or like operations, whether formed from flat sheet or tube or otherwise.

Hollow sheet metal blades, whether manufactured from tube or fabricated from flat sheet, have many attractive attributes, but the problem of their anchorage is a difficult one, particularly in their application to gas turbine rotors in aircraft power plants where the need for light weight and cheapness of manufacture has to be reconciled with severe operating conditions, in which the blading is exposed to elevated temperatures and subjected to high centrifugal stress and may be to intermittent loads which in some cases may excite damaging vibrations. One object of the invention, accordingly, is to provide a blade and mounting therefor in which there is adequate distribution of the loads imposed on the root and undesirably stressed formations are avoided. As well as fulfilling this requirement and affording a convenient and adequately strong means of attachment between blades and a rotor wheel or disc the invention may be so applied as to afford the possibility of internal cooling by the passage of air or other fluid radially along the interior of the blades. Primarily however the invention is concerned with providing a construction of blade, and manner of attachment thereof to a turbine rotor, which will be economical in manufacture and will reduce expensive or highly precise operations to a large extent, to which end use is made of a preferably unthickened continuation of the sheet metal blade to form the blade root, and of forms of anchorage designed to accommodate such a root without excessive manufacturing cost. Another advantage of the invention is in some instances to afford means whereby one or more blades may be removed and replaced with comparative ease and without disturbing the remainder.

Broadly speaking the invention resides in providing an axial flow turbine rotor assembly having hollow tubular sheet metal blades mounted thereon whose root construction comprises pe-

2

ripherally spaced axially disposed sheet metal wall portions each of which is a generally radial continuation of the blade wall base and has a deformation in the peripheral direction produced by pressing, stamping, or a like sheet metal working operation by which it is adapted to make blade-retaining engagement with a corresponding formation afforded in a generally radial and axially disposed slotted anchorage formed in said rotor, the blade roots so formed being held in secure relationship with their anchorages by spacing means within said slots acting to prevent displacement of the blade-retaining formations of said wall portions in the peripheral direction with the corresponding formation of its anchorage.

The root construction and anchorage proposed enables root loads to be properly balanced and provides adequate stability; further to improve stability, the two spaced walls may be supplemented by one or more further walls to form a three or a four sided box construction. Moreover, the blade root may have at least one wall outside and axially spaced from the flank of the bladed element to form a radially extending air duct which is arranged to communicate with a passage through the blade to allow a flow of cooling air therethrough.

It will be appreciated that the expressions "axial direction" and "peripheral direction" are used herein primarily to mean directions parallel respectively with the axis of rotation and the plane of rotation of the turbine rotor. It is to be observed, however, that in general the anchorages and formations employed in the various embodiments of the invention need not be strictly in the axial or the peripheral direction, as the case may be, but may be inclined thereto; the expressions referred to, when used in relation to the direction of anchorages or formations, are therefore to be read as including the inclined arrangements.

Other and more detailed features of the invention will appear from the following description with reference to the accompanying drawings, which illustrate by way of example a number of constructional forms of the invention and in which:

Figure 1 is a fragmentary sectional side elevation of a turbine rotor blade mounting embodying a simple form of blade root and anchorage in which the root has axially extending walls co-operating with axially extending slots;

Figure 2 is a section on line 2—2 of Figure 1; Figure 3 is a perspective view illustrating a

blade root of three-sided box-like construction;

Figure 4 is a fragmentary section in the axial plane of a rotor having applied thereto a blade as illustrated in Figure 3;

Figures 5 and 6 are perspective views illustrating methods of making a blade root of four sided box-like construction;

Figure 7 is a peripheral section through the blade roots assembled as in Figure 6.

Referring now in more detail to the examples illustrated in the drawings, in Figures 1 and 2 the turbine wheel or rotor 1 is formed at its periphery with radial slits as at 2 of a width sufficient to accommodate two thicknesses of the sheet metal employed, said slits extending through the rotor in the axial direction and being keyholed by drilling in the axial sense to form two bores as at 3 in each slit. This forms in effect a rim of radial teeth 4 in which the flank of each tooth has practically semi-cylindrical grooves running axially. The blades have hollow sheet metal bodies 5 made, for example, by processing lengths of tube, radially inward extensions of which form spaced parallel walls 6 adapted to lie in the slits 2. Each wall is deformed in the peripheral direction about an axis extending in the axial direction by a pressing or like operation to provide corrugations or ribs as at 7 complementary with respect to the grooves formed by the two halves of each bore 3. Adjacent blade roots are entered over successive teeth 4, each root with its walls 6 in adjacent slits 2 and their respective ribs 7 engaging the grooves afforded by the bores 3 at one side of the corresponding slit. Locking means in the form of cylindrical or very slightly tapered pins 8 are then inserted or driven into the practically circular bores formed by the adjacent ribs 7 of the adjacent blade walls 6. Adjacent blades are thus locked both to the wheel and in respect of each other, the inserted pins 8 effectively resisting radial load tending to pull the blades off, and the multiplicity of the anchorage points so provided effecting a distribution of the load over the root wall. Such distribution may be, and in practice preferably is further improved by increasing the number of grooves. It will be noted that this construction lends itself to cheapness of manufacture in that the formation of the slits 2 and holes 3 involve simple cutting and drilling operations only, whilst the security of the mounting is such that unthickened continuations of the blade wall may be used to form the root, thus avoiding the complications involved in providing such a thickening. As illustrated in the figures, the pins may be made hollow, both with the object of allowing coolant air or the equivalent to pass through them and to permit such slight distortion during their insertion as may be desirable to accommodate elasticity or manufacturing error of the blade roots. The remaining blades are of course entered and secured in the same way all around the wheel. In the example illustrated, axial disturbance of the blades is prevented by riveting over the ends of the pins.

The modified construction illustrated in Figures 3 and 4 follows the same general principles as that illustrated in Figures 1 and 2, but the root has a third wall 9 so as to form a rectangular U-shape in peripheral cross section, the wall 9, in addition to forming a tie which renders the whole structure more rigid, preventing displacement of the blade in one axial direction. Since in use, the axial thrust tending to displace the

blade is unidirectional, the wall 9 will be sufficient in itself to resist such displacement if positioned at the appropriate side of the rotor 11; as an additional safeguard, however, since the grooves 7 must stop short of the wall 9 and thus the pins 8 cannot pass completely through the rotor for riveting, partial fourth walls 10 may be provided, by tabs or extensions on at least one of the walls 5 which are turned over after positioning the blade and inserting the pins 8, and if desired are welded or otherwise secured in place against the rotor. In this construction also (see particularly Figure 4) the third wall 9 is arranged to be spaced away from the flank of the rotor, as by the indentations 11, so as to form a duct leading from a radially inner locality into the interior of the blade for the passage of cooling air. As in the previously described embodiment, the number of grooves may be more than two.

As indicated in Figure 5 the last described construction may be further modified and rendered even more rigid by the provision of a root having a fourth complete wall 12. In this case both the wall 12 and the wall 9 are formed by downward extensions of the blade body 5 separate from the walls 6 to allow the grooves 7 in the latter to extend from edge to edge, the walls 9 and 12 having at their edges corresponding recesses 13 which register with the ends of the grooves. One or both of the walls 9, 12 may be left in the dotted position shown until the blade has been applied to the rotor, and then turned down, being then held in place by inserting locking pins 8 as before and riveting over the heads, and if desired by welding to the edges of the walls 6. An air passage is again provided for example by a pressed rib 11a, as shown, or by indentations such as are shown in Figures 3 and 4. As an alternative (see Figure 6) to the construction illustrated in Figure 5, the sides 6 and 9 may be of integral U-shape as in Figure 3, with the fourth wall 12 formed by a grooved or corrugated extension of one of the walls 6 which is bent into position about a radial line after inserting the locking pins 8, the rotor having peripherally extending recesses 1a to receive the corrugations of the wall 12. When a corrugated sheet is bent about a line transverse to the corrugations it will be found that the corrugations flatten out at and adjacent to the bend, the vertex tending to become a straight line. The right-hand side of Figure 6 shows an extension 12 of a wall 6, with the corrugations 7 extending into it, before bending. When the extension 12 is bent to lie against the face of the rotor and so form a fourth wall to the blade root the corrugations become turned from the axial into the peripheral direction and are received by the recesses 1a in the rotor. The flattening out of the corrugations 7 at and adjacent to the vertex of the angle between the extension 12 and the wall 6 involves the enclosure of the end of the locking pin 8. The finished formation is that of the middle blade in the perspective view of Figure 6, and the same formation is shown in peripheral section in the right-hand side of Figure 7, the section being taken on the center line of the corrugations. The end wall 9 in this case also may be formed to provide an air duct, as by the methods of Figures 4 or 5.

If it be desired to improve the distribution of loads in the anchorage, the rim of the wheel may be indented between the anchorages, as at 14 in Figure 1, so as to afford appreciable resilience

and therefore to enable radially spaced ribs and grooves the better to share the main loads, whilst incidentally affording the possibility of substantial frictional gripping between the flat surfaces of the slots and walls. The indentation may also be used to afford an inlet for cooling air by carrying it lower than the skirt of the blade as seen in Figure 1.

It is of course not necessary in any of the constructions illustrated in Figures 1 to 7 that the slots in the rotor rim should be strictly axial since they may lie at an inclination, the walls of the blades where necessary being correspondingly distorted from a rectangular arrangement to that of a parallelogram.

It would be apparent from a consideration of the foregoing that various combinations of the devices mentioned can be utilised and are within the scope of the invention.

It will be appreciated that the various constructions of root mountings described in the foregoing, by virtue of the distribution of the load over substantially the whole of the root area, and its balancing through the generally parallel symmetrically disposed root walls, offer favourable conditions for sustaining severe stresses.

I claim:

1. An axial flow gas turbine rotor assembly comprising a rotor wheel having around its periphery a plurality of axially extending slits each opening out, below the periphery, into an axially extending blade anchorage hole, a plurality of hollow tubular sheet-metal blades disposed around the periphery of said wheel, two peripherally spaced and separately anchored root portions on each said blade, one being a generally radially inward continuation of one of the axially extending sheet metal walls of the blade fitting in one of said slits and passing therethrough into a blade anchorage hole wherein it is bulged out to fit the hole, the other of said root portions being a similar continuation of the opposite wall of the blade likewise disposed in another one of the said slits and holes, in combination with a blade-retaining peg extending through each said anchorage hole and engaging said bulged blade-root portion.

2. A turbine rotor as set forth in claim 1 wherein the said pegs are tubular rivets each passing through one of said blade anchorage holes and secured to the sheet metal forming one of said blade root portions.

3. A turbine rotor as set forth in claim 1 wherein said wheel has a rim made up of axially extending radial teeth alternating with undulations, each said slit being formed in one of said teeth.

4. A turbine rotor as set forth in claim 1 wherein each said blade has at least a third root portion which is a wall also continuing radially inward from the blade and joining the other two root portions, said third wall lying beside the flank of said rotor wheel and having a spacing member engaging said flank and separating said third wall from said flank to leave open a passage into the interior of said hollow blade.

5. An axial flow gas turbine rotor assembly comprising a rotor wheel having around its pe-

riphery a plurality of axially extending slits each opening out, below the periphery, into an axially extending blade anchorage hole, a plurality of hollow tubular sheet-metal blades disposed around the periphery of said wheel, two peripherally spaced root portions on each said blade, anchored separately from each other, one being a generally radially inward continuation of one of the axially extending sheet metal walls of the blade abutting against a like root portion of one neighbouring blade, the other of said root portions being a similar continuation of the opposite wall of the blade abutting similarly against the other neighbouring blade root, each pair of 10 said abutting blade root portions fitting in a separate one of said slits and passing therethrough into a blade anchorage hole, wherein they are bulged apart to fit said hole, in combination with a blade-retaining peg extending 15 through each said anchorage hole and fitting between said bulged-apart blade-root portions.

6. An axial flow gas turbine rotor assembly comprising a rotor wheel pierced in the axial direction by a plurality of keyhole slots extending inwards from its periphery, a plurality of hollow tubular sheet-metal blades disposed around the periphery of said wheel, two peripherally spaced root portions on each said blade, anchored separately from each other, one being a generally radially inward continuation of one of the axially extending sheet metal walls of the blade abutting against a like root portion of one neighbouring blade, the other of said root portions being a similar continuation of the opposite wall of the blade abutting similarly against the other neighbouring blade root, each pair of 20 said abutting blade-root portions fitting in a separate one of said keyhole slots, the walls being spread apart to conform to the shape of the cylindrical part of the keyhole slot and leave a central opening, in combination with a blade-retaining peg extending through each said central openings in said keyhole slots.
